United States Patent Office

Des. 214,294
Patented May 27, 1969

214,294

BOAT

Mack E. Stevens, 3656 Vigilance Drive,
Palos Verdes, Calif. 90274

Continuation of design application Ser. No. 7,620, June
27, 1967. This application Feb. 23, 1968, Ser. No. 10,704

Term of patent 14 years

Int. Cl. D12—06

U.S. Cl. D71—1

FIG. 1.

FIG. 2.

FIG. 3.

FIG. 5.

FIG. 4.

FIGURE 1 is a perspective view of the boat design;
FIGURE 2 is a top plan view thereof;
FIGURE 3 is a side elevational view thereof;
FIGURE 4 is a front elevational view thereof; and
FIGURE 5 is a rear elevational view thereof.

This application is a continuation of my earlier-filed copending application Ser. No. D. 7,620 filed June 27, 1967, now abandoned.

I claim:

The ornamental design for a boat, as shown.
